US0D1084759S

(12) **United States Design Patent** (10) **Patent No.:** **US D1,084,759 S**
(45) **Date of Patent:** **** Jul. 22, 2025**

(54) **WHIPPED PRODUCT DISPENSER**

(71) Applicant: **Rich Products Corporation**, Buffalo, NY (US)

(72) Inventors: **Ralf Reiser**, Orchard Park, NY (US); **Kenneth Berquist**, Getzville, NY (US); **Shawn Campbell**, Burlington (CA)

(73) Assignee: **Rich Products Corporation**, Buffalo, NY (US)

(**) Term: **15 Years**

(21) Appl. No.: **29/983,953**

(22) Filed: **Jan. 13, 2025**

Related U.S. Application Data

(63) Continuation of application No. 29/856,890, filed on Oct. 18, 2022, now Pat. No. Des. 1,057,502, which is a continuation of application No. 29/749,430, filed on Sep. 4, 2020, now Pat. No. Des. 966,799.

(57) **CLAIM**

The ornamental design for a whipped product dispenser as shown and described.

DESCRIPTION

FIG. 1 is a front perspective view of a whipped product dispenser, showing our new design.

FIG. 2 is a rear perspective view thereof.

FIG. 3 is a left-side view thereof.

FIG. 4 is a right-side view thereof.

FIG. 5 is a front view thereof.

FIG. 6 is a rear view thereof.

FIG. 7 is a top view thereof; and,

FIG. 8 is a bottom view thereof.

The portions of the design illustrated in broken lines are included for the purpose of illustrating environment and form no part of the claimed design.

1 Claim, 8 Drawing Sheets
